FREDERICK R. ERBACH, OF DETROIT, MICHIGAN, ASSIGNOR TO KELVINATOR CORPORATION, OF DETROIT, MICHIGAN, A CORPORATION OF MICHIGAN

COMPRESSOR VALVE

Application filed June 17, 1927. Serial No. 199,442.

My invention relates to compressor valves for mechanical refrigerating compressor units and it has particular relation to a novel type of pressure actuated exhaust valve therefor.

Heretofore, compressor cylinders have been provided with exhaust valves actuated by pressure within the cylinder in which the valve closing member and seating spring therefor were inclosed within a housing resiliently held in position by means of a second spring and a housing enclosing the entire unit. Both housings were provided with outlet ports, but, as the inner housing was necessarily movable with respect to the outer housing, it frequently moved to such position that exhaust ports in one or both of the housings were closed or partially closed by portions of the other housing thus impairing the efficiency of the compressor.

One object of my invention is to provide a novel type of exhaust valve wherein the exhaust ports of the housings are always maintained in alignment without interfering with the proper movement of the inner housing.

Another object of my invention is to provide a novel type of housing member which is simple, inexpensive to manufacture, and which lends itself readily to cooperation with an associated housing to prevent undesirable relative movement therebetween.

For a more comprehensive understanding of my invention reference may now be had to the accompanying drawings of which:

Fig. 1 is a cross-sectional view of a portion of a compressor cylinder provided with an exhaust valve embodying my invention; and

Fig. 2 is a side elevational view of an outer housing member constructed in accordance with my invention; and

Fig. 3 is a bottom plan view of the housing illustrated in Fig. 2; and

Fig. 4 is a plan view of an inner housing member constructed in accordance with my invention; and

Fig. 5 is a side elevational view of the housing shown in Fig. 4; and

Fig. 6 is a bottom plan view of the housing illustrated in Figs. 4 and 5; and

Fig. 7 is a perspective view of the inner and outer housings assembled in cooperative relation; and

Fig. 8 is a bottom plan view of the housings assembled as shown in Fig. 7.

Referring first to Fig. 1, have shown a compressor cylinder 10 provided with a piston 11 and a cylinder head 12. The cylinder head 12 is provided with an exhaust port 13, the passage of compressed fluid through which is regulated by a valve mechanism 14, constructed in accordance with my invention. The valve mechanism 14 is enclosed within an outlet chamber 15 in a cylinder top 16. A fluid conduit 17 secured to the cylinder top 16 is normally in open communication with the chamber 15 and serves to connect it to a condensing coil (not shown) of the refrigerating system.

The cylinder head 12 is provided with an annular raised portion 18 immediately surrounding the exhaust port 13, which serves as a valve seat for a suitable valve closing member 19, and with an annular groove 20 immediately surrounding the raised annular valve seat 18.

The valve closing member 19 is a thin flexible metallic disc and is resiliently held in position upon the seat 18 by means of a helical compression spring 21. A housing member 22 is provided with a centrally depressed portion 23, the face of which is flat and serves as a stop member for the valve closing member 19. The depressed portion 23 is provided with a small opening 23a therein, which serves to prevent the formation of a vacuum between the valve closing member 19 and the face of the member 23, when they are in engagement. The housing 22 is also provided with a plurality of spaced integral downwardly projecting supporting legs 24, the ends of which are adapted to rest in the groove 20 in the cylinder head 12. Intermediate the legs 24, the housing 22 has a plurality of outwardly extending integral projections 25, for a purpose to be hereinafter explained.

The housing 22 is resiliently held in its lowermost position, with the ends of the legs 24

24 in the bottom of the groove 20, by means of a helical compression spring 26, the other end of which is compressed and held in position by means of an outer housing 27. The housing 27 is provided with a raised central portion 28 which engages one end of the spring 26 and which is provided with a central outlet port 29. At the base of the raised central portion 28, the housing 27 has an outwardly flared portion 30 which serves as a stop member for the housing 22 and from which extends spaced downwardly projecting integral supporting legs 31. The lower ends 32 of the legs 31 are rigidly secured to the cylinder head 12 by means of screws or bolts 33.

As best shown in Figs. 7 and 8, the spaces between the spaced legs 24 of the housing 22 serve as exhaust ports from the housing 22 and the spaces between the spaced legs 31 of the housing 27 serve as exhaust ports therefrom. The outwardly extending projections 25 of the housing 22 extend between the legs 31 of the housing 27, thus permitting the housing 22 to move toward and away from the stop portion 30 of the housing 27 but prevent relative rotative movement of the two housings.

From the foregoing description it will be apparent that the housing 22 may move freely against the action of the spring 28 toward and away from the valve seat 18 but that the lugs or projections 25 of the housing 22 moving between the legs 31 of the member 27 will prevent any rotative movement of the housing 22, thus retaining the exhaust ports of the housings 22 and 27 always in alignment and always open.

Although I have illustrated but a single form of my invention, and have described in detail but a single application thereof, it will be apparent to those skilled in the art that it is not so limited, but that various modifications and changes may be effected therein without departing from the spirit of my invention or from the scope of the appended claims.

I claim as my invention:—

1. In a discharge valve, a valve seat, an independently reciprocable valve closing member adapted to engage said seat, a spring member adapted to engage said valve closing member, a reciprocable housing for said spring member, and means for preventing rotary movement of said housing.

2. In an automatically actuated discharge valve for compressors, a valve seat, an independently reciprocable valve closing member, a spring member engaging said valve closing member and causing it to resiliently engage said seat, a reciprocable housing for said spring, and means for preventing rotary movement of said housing.

3. In a pressure operated discharge valve, a valve seat, an independently reciprocable

valve closing member, a spring member engaging said valve closing member and causing it to resiliently engage said seat, a resiliently mounted reciprocable housing for said spring member, and means for preventing rotary movement of said housing. 70

4. In a pressure operated discharge valve, a valve seat, an independently reciprocable valve closing member, a spring adapted to engage said valve closing member, a reciprocable housing for said spring member, a second spring member engaging said housing, a stationary housing for said second spring member, and means for preventing rotative movement of said reciprocable housing. 75

5. In a pressure operated valve for compressors, a valve seat, an independently reciprocable valve closing member, a spring member engaging said valve closing member, a reciprocable housing enclosing said spring member and valve closing member and provided with outlet ports, a second spring member engaging said housing, a stationary housing enclosing said valve closing member, said reciprocable housing and said springs and provided with outlet ports, and means for maintaining the ports in said housings in alignment. 85

6. In a pressure operated valve for compressors, a valve seat, an independently reciprocable valve closing member, a spring member engaging said valve closing member, a reciprocable housing enclosing said spring member and valve closing member and provided with outlet ports, a second spring member engaging said housing, a stationary housing enclosing said valve closing member, said reciprocable housing and said springs and provided with outlet ports, one of said housings being provided with projections adapted to enter the ports in the other housing. 95

7. In a pressure operated valve for compressors, a valve seat, an independently reciprocable valve closing member, a spring member engaging said valve closing member, a reciprocable housing enclosing said spring member and valve closing member and provided with outlet ports, a second spring member engaging said housing, a stationary housing enclosing said valve closing member, said reciprocable housing and said springs and provided with outlet ports, said reciprocable housing being provided with projections adapted to enter the ports in said stationary housing. 100

8. In a pressure operated valve for compressors, a valve seat, an independently reciprocable valve closing member, a spring member engaging said valve closing member, a reciprocable housing provided with spaced legs enclosing said spring member and valve closing member, and with a depressed central portion adapted to act as a stop member for said valve closing member, a second spring member engaging said housing, a stationary 115

housing member enclosing all of said valve parts and provided with spaced supporting legs, and means for maintaining the supporting legs of said housings in radial alignment.

- 5 9. In a pressure operated compressor valve, a cylinder head provided with an exhaust port and valve seat, an independently reciprocable valve closing member, a spring member engaging said valve closing member,
- 10 a loosely mounted reciprocable housing provided with spaced supporting legs enclosing said spring member and valve closing member and with a depressed central portion adapted to act as a stop member for said valve
- 15 closing member, a second spring member engaging said housing, a stationary housing member enclosing said last named spring member and provided with spaced supporting legs surrounding said reciprocable housing,
- 20 and means for securing the legs of the outer housing to the cylinder head, said reciprocable housing being provided with means preventing rotative movement thereof.

10. In a pressure operated compressor valve, a cylinder head provided with an exhaust port having a valve seat associated therewith, an annular groove surrounding said exhaust port, an independently reciprocable valve closing member, a spring engaging said valve closing member, a reciprocable housing provided with spaced supporting legs enclosing said spring and said valve closing member and adapted to rest in said groove, a spring engaging said housing and tending to retain said legs in said groove, a stationary housing enclosing said last named spring member and provided with spaced supporting legs enclosing said first mentioned housing and means for securing the legs of
- 35 said stationary outer housing to the cylinder head, said inner reciprocable housing being provided with outwardly extending projections adapted to fit between the legs of said stationary housing.
- 40

- 45 In testimony whereof I hereunto affix my signature.

FREDERICK R. ERBACH.
